UNITED STATES PATENT OFFICE.

PAUL P. BROCK, OF GILLESPIE, ILLINOIS.

MUSIC-LEAF TURNER.

Application filed May 31, 1921. Serial No. 473,720.

To all whom it may concern:

Be it known that I, PAUL P. BROCK, a citizen of Germany, having made application and filed petition to become a citizen of the United States, residing at Gillespie, in the county of Macoupin and State of Illinois, have invented certain new and useful Improvements in Music-Leaf Turners; and I do hereby declare the following to be a full, clear, and exact description of the invention, such as will enable others skilled in the art to which it appertains to make and use the same.

The present invention relates to music leaf turners, and aims to provide a novel and improved device of that kind having improved features of construction to enhance the utility and efficiency thereof.

Another object of the invention is the provision of a music leaf turner having novel means for engaging the leaves or pages for turning them one after the other, and providing for the convenient application and removal of the book.

A further object is the provision of novel means for actuating the leaf turning members and for latching and releasing them one at a time.

A still further object is the provision of such a device having novel means for clamping or holding the covers of the book or those pages which are not to be turned.

The invention has for another object the provision of novel means for fastening the device to an ordinary music stand.

A further object is the provision of an attachment for a music stand to enable the music leaf turner to be controlled by the foot.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawings, wherein:

Figure 1 is a front view of the music leaf turner.

Fig. 2 is an enlarged section on the line 2—2 of Fig. 1.

Fig. 3 is an enlarged section on the line 3—3 of Fig. 1 showing the clamp for one cover of the book.

Fig. 4 is a front view showing the device applied to a music stand with the foot attachment applied.

Fig. 5 is a vertical section on the line 5—5 of Fig. 4.

Fig. 6 is an enlarged plan view of the clamping bars for attaching the music leaf turner to the music stand, portions being shown in section.

Fig. 7 is a section on the line 7—7 of Fig. 6.

Fig. 8 is a perspective view of one of the lower leaf holding hooks.

In carrying out the invention, there is provided a portable back rest for the book of music, the term "book" being used to include sheet music also. This back rest includes a rectangular frame 10 having a lower plate 11 in rear of the lower portion of the frame and extending upwardly for a distance above such lower portion. A strip 12 of felt or other suitable material is secured to the lower edges of the frame 10 and plate 11 and is tucked up between said frame 10 and plate 11 to form a groove for engaging over the lower edge or flange of an ordinary rest or support, as depicted in Fig. 3. A wire or rod 13 is secured at its terminals to the side or end members of the frame 10 for supporting the book within the frame, such frame being large enough to receive books of different sizes therein.

Means are provided for clamping the covers 14 of the book and also those pages or leaves which are not to be turned, and include clamps 15 hinged, as at 16, to the lowest bar of the frame 10 near the opposite end thereof, and swung against the plate 11 by means of springs 17. These clamps 15 can overlap the lower end portions of the book covers 14 and the leaves which are not to be turned for clamping them back against the plate 11, and thereby holding the book open in the frame.

In order to conveniently swing the clamps 15 forwardly away from the plates 11 for convenience in applying the book to the back rest of the device, rock shafts 18 are journaled in bearings 19 carried by the plate 11 and extend behind the hinges 16 and to the opposite ends of the frame. These shafts 18 have bent arms 20 behind the clamps 15, and have operating arms 21 adjacent to the end members of the frame. Said arms 21 can be conveniently grasped by the thumb and finger and swung forwardly, whereby

the arms 20 in swinging likewise will swing the clamps 15 to open position, for the insertion of the book covers 14 and desired leaves behind the clamps. Then, by releasing the arms 21, the clamps 15 are swung by the springs 17 to hold the covers and leaves of the book which were inserted behind said clamps.

The leaf turning members or means include a plurality of rock shafts 22 midway between and parallel with the end members of the frame 10 and having their end portions journaled in bearings 23 carried by the upper bar of the frame and the plate 11, for the turning movement of said shafts. The shafts have the angularly-extending arms 24 and 25 at their upper and lower ends, respectively, provided with the terminal eyes 26 for the engagement of snap hooks or other attaching couplings 27 secured to the opposite ends of leaf-engaging wires 28. Although wires are specified for the leaf-engaging members, they may be strings or other suitable elements to extend across the respective leaves of the book. The wires 28 are readily placed across corresponding pages or leaves of the book to be turned, and their ends fastened by the hooks or couplings 27 with the eyes 26 of the arms 24 and 25, after the book has been placed against the back rest and fastened by the clamps, with the leaves to be turned free between said clamps. The arms 24 are located above and below the upper and lower edges of the book, respectively, and the wires 28, although they extend across the pages, will not interfere with the reading of the music.

Means are provided for swinging the leaf-turning members so as to turn the leaves or pages one after the other, and, for this purpose, the lower arms 25 of the leaf-turning members have loops 29 to which cords or flexible elements 30 are attached, and said cords pass rearwardly through an opening 31 in the plate 11 to the left of the shafts 22. It is preferable to provide rollers 32 in the opening 31 for the passage of the cords 30 between them, to reduce friction. The other terminals of the cords 30 are connected to retractile coiled springs 33 at the rear of the plate 11 and anchored thereto, as at 34. When the arms 24 and 25 are swung toward the right, the cords 30 are pulled with the arms 25, thereby stretching the springs 33, and when said arms 25 are released, the springs will swing said arms to the left by pulling the cords 30 to the left and moving the loops 29 into the opening 31, thereby turning the leaves to the left in succession as the successive leaf-turning members are released.

A set of latches is provided for holding the leaf-turning members in set position at the right, and such latches include depending stems 35 slidable in a guide member 36

secured to the lower bar of the frame 10 at the right of the shafts 22. These stems have latch fingers 37 at their upper ends to engage the respective arms 25. Said arms are spaced apart vertically, and the fingers 37 are of different lengths, whereby the leaf-turning members are released in succession when the latches are depressed from the left to the right in succession. The latches are raised by springs 38, and have finger pieces 39 at their lower ends extending forwardly to be depressed by the finger for convenience in releasing the leaf-turning members in succession.

After the book has been properly placed in the frame and held by the clamps 15, and the wires 28 disposed across the corresponding leaves and fastened to the arms 24 and 25, said arms are swung to the right and the arms 25 held in place by the latch fingers 37. By depressing the first latch stem 35, the first leaf-turning member is released and will swing to the left for turning the corresponding leaf, and the other leaves are turned by depressing the other latch stems 35 in succession. By detaching the wires 28 from either the upper or lower arms of the leaf-turning members, and releasing the clamps 15, the book is readily removed and another one substituted, or by leaving the book in the frame, the wires 28 can be inserted between other pages or leaves when another selection is made from the same book. The device can be readily placed on the ordinary music rest or support of a piano, organ, or the like, and can also be used on music stands.

In using the device on a music stand, a clamp is provided for holding the frame 10 of the device in place on the stand. The stand, as well known, includes the standard 40 and the back rest or support 41 carried thereby having a lower flange 42 for supporting the book or sheet music. The clamp includes three clamping bars 43, two of which are in alinement with adjacent ends overlapping, and the other having one end portion extending across said overlapping portions. The adjacent end portions of the bars have longitudinal slots 44 through which a clamping bolt 45 engages, and the remote or outer ends of the bars have hooks 46 extending forwardly and carrying clamping screws 47. In using the device on a music stand, the frame 10 is placed in front of the back rest or support 41 and the strip 12 engaged over the flange 42, as seen in Fig. 5. The clamp is placed behind the rest 41 and the bolt 45 is loosened, whereby the bars 43 can be adjusted. The hooks 46 of the alining bars 43 are engaged over the end members of the frame 10, and the hook 46 of the other bar engaged over the upper member of the frame, as seen in Fig. 4. The bolt 45 is then tightened, to

clamp the bars 43 together, and the screws 47 are then tightened to clamp the frame 10 in place. This will hold the device on the music rest without liability of the parts 5 becoming displaced accidentally.

When using the device on a music stand an attachment is preferably used to enable the latches to be operated by the foot, especially when the player cannot conveniently operate the latches by hand. This attachment includes a supplementary standard 48 comprising the upper bar or section 49 having a clamp 50 at its upper end to engage the lower right hand portion of the frame 10, and a lower bar or section 51 having the diverging feet 52 to rest on the floor. The adjacent terminals of the bars 49 and 51 overlap one another and have series of apertures 53 to register in the different adjustments of the standard 48 to correspond with the adjustment of the standard 40. A U-bolt 54 is insertible through registering apertures 53, and an elongated washer 55 is engageable on the terminals of the bolt, 25 and the parts clamped together by nuts 56 or other retaining elements engaged on the terminals of the bolt.

Upper and lower horizontal guide bars 57 are attached to the bars 49 and 51 of the standard 48, and have clamps 58 of any suitable kind to embrace the standard 40. Actuating members 59 are slideable upwardly and downwardly in the bars 57, there being one of said members for each 35 latch of the leaf-turning device. Each of the members 59 includes the upper and lower bars or section 60 and 61 having their adjacent terminals overlapping, similar to the sections or bars of the standard 48. The 40 bars 60 have rearwardly extending portions 62 at their upper ends extending over and resting on the finger pieces 39 for the detachable engagement of the latches and bars, and the bars 61 are provided at their 45 lower ends with foot pieces 63 to be readily depressed in succession by the foot of the player. The bars 60 and 61 of the members 59 are adjustably connected similar to the bars or sections of the standard 48. Thus, 50 the overlapping terminals of the bars 60 and 61 have the series of apertures 64 to register for the insertion of U-bolts 65 on which the elongated washers 66 are engaged and also the nuts 67 or retaining elements. The members 59 are thus adjustable longitudinally to different lengths according to the adjustment of the standards 40 and 48 to space the foot pieces or pedals 63 a convenient distance above the floor, and, if desired, a block 68 can be placed 60 on the floor under said foot pieces to limit the depression thereof.

When the foot attachment is thus applied, the latches can be released in succession by the foot of the player, and the

depression of the foot pieces 63 will pull the members 59 downwardly, so that the portions 62 thereof will pull the latches down also. However, if desired, the latches can still be depressed by hand.

It is preferable to extend the bills 27' of the lower hooks 27 of the wires 28, so that said hooks can be engaged over the lower edges of the leaves, to prevent the leaves from sticking or adhering together when turning the leaves, and thereby holding the leaves against the respective wires 28. This will avoid the accidental turning of one leaf with the other.

Having thus described the invention, what is claimed as new is:—

1. A music leaf turner comprising rock shafts having arms to be disposed above and below the leaves, wires to extend across the leaves having coupling members at their ends to engage said arms, and means for swinging said arms.

2. A music leaf turner comprising a frame, a set of rock shafts carried by the frame and having upper and lower arms to be disposed above and below a book supported by the frame, wires to extend across the leaves of the book, hooks at the ends of said wires to engage said arms and means for swinging said arms.

3. A music leaf turner comprising a frame for supporting a book, spring-pressed clamps hinged to the frame to overlap and hold the covers of the book and arranged to swing away from the frame, manually operable members extending behind the clamps for swinging said clamps open, and leaf-turning members carried by the frame.

4. A music leaf turner comprising a frame for supporting a book, leaf-turning members carried by the frame for swinging movement at the front of the frame, retractile springs carried by the frame at the rear thereof, said members having loops, flexible elements connected to said loops and springs, the frame having an opening through which said flexible elements extend and into which the loops are moved when said members are swung by the springs, and latches for holding said members when they are swung to pull the flexible elements and stretch the springs.

5. A music leaf turner comprising a frame for supporting a book, spring-actuated leaf-turning members carried by the frame, latches carried by the frame for holding said members and operable by the fingers for releasing said numbers in succession for turning movement, means for clamping the frame on a music stand, and means attachable to such stand and including foot-operable members to detachably connect with said latches.

6. A music leaf turner comprising a frame for supporting a book, spring-actuated leaf-turning members carried by the frame,

latches carried by the frame for holding said members and releasing them in succession for turning movement, foot-operable members detachably engageable with said latches, and means for guiding said foot-operable members and retaining same in operative relation with the frame.

7. A music leaf turner comprising a frame for supporting a book, spring-actuated leaf-turning members carried by the frame, latches carried by the frame for holding said members and releasing them for turning movement in succession, a standard having means for attachment to said frame, guiding

means attached to said standard and having 15 means for attachment to a music stand, and members slidably in said guiding means having portions at their upper ends to engage said latches and having foot pieces at their lower ends.

20 In testimony whereof I have signed my name to this specification in the presence of two subscribing witnesses.

PAUL P. BROCK.
